FIG 3.

FIG. 6.

FIG. 4.

FIG. 5

A cross-sectional diagram of a ring-shaped device. The outermost layer is a thick, hatched ring labeled 3. Inside this is a thinner ring labeled 10. The center of the device is a solid, unshaded area. Numbered callouts point to specific features: callout 1 points to the top edge of the outer hatched ring; callout 4 points to the bottom edge of the outer hatched ring; callout 11 points to a small triangular protrusion on the right side; callout 9 points to a vertical line segment on the right side; callout 13 points to a horizontal line segment on the right side; and callout 12 points to a vertical line segment on the right side, positioned below callout 9.

RADIATOR CAP.

Application filed October 3, 1921. Serial No. 504,851.

The present invention relates to improvements in tank and other closure caps or plugs for general closure purposes but has particular reference to radiator caps for automobiles and other motor vehicles and resides in the provision of a cap which is constructed and arranged so that when once fitted into place it is automatically locked against removal, access to the radiator, tank or other object with which the cap is used, being had thru a closure permanently or non-removably attached to and forming a part of the cap.

The ordinary radiator cap for automobiles and the like is frequently lost due to failure to screw the cap back into place after filling the radiator and due to the unscrewing of the cap and falling of the same, off the neck while the vehicle is in motion. Radiator caps of the ordinary screw-on-removable type are also frequently stolen, particularly when such caps support temperature and level indicators or ornaments. We are also aware of closure caps or plugs, particularly in the case of radiator caps, wherein a hinged closure is used instead of a screw cap or plug, but these devices are not universally applicable to different makes of automobiles without necessitating changes in the construction of the neck of the radiator.

It is the primary object of the present invention to provide a closure cap or plug of the character described, which in the form of a radiator cap for automobiles and the like, may be readily applied to various makes of automobiles without necessitating any change in the construction of the neck of the radiator, the device of our invention comprising essentially a body portion and a closure therefor, which is permanently, that is non-removably, attached to the body portion, the body portion being constructed so that it may be attached to the neck of a radiator by the simple expediency of removing the ordinary radiator cap and fitting the body portion in place, whereupon the body portion will automatically lock, and since it cannot be removed, the entire cap of this invention will become a permanent fixture upon the radiator, thus preventing loss of the cap thru inadvertence or carelessness, or by theft.

An other object of the invention is to provide a radiator cap of the character de-

scribed which is constructed so that the means 55 providing for access to the radiator thru the cap, serves as an ornament.

Another object of the invention is to provide a novel, simple and effective locking arrangement forming a part of the cap of this 60 invention, which arrangement is such that after removing the ordinary cap from the radiator and screwing the cap of the present invention in place, it will cause the cap of this invention to be permanently locked against 65 being unscrewed and removed from the neck, it being necessary to resort to machine work, such as drilling or boring, in order to gain access to the locking means to effect a release 70 thereof.

The invention further resides in the provision of a cap of the character described which includes means for supporting a temperature indicator, ornament or other device, in such manner that the indicator, ornament 75 or other device will be locked against removal by unauthorized persons.

The invention possesses other advantages and features some of which, with the foregoing will be set forth at length in the following description where we shall outline in full that form of the invention which we have selected for illustration in the drawings accompanying and forming a part of the present specification. In said drawings we 80 have shown one form of the construction of our invention, but it is to be understood that we do not limit ourselves to such form since the invention as expressed in the claims may be embodied in a plurality of forms. 90

Referring to the drawings:

Fig. 1 is a front elevation of the cap of this invention showing it as it would appear when in use.

Fig. 2 is a front elevation of the cap showing it with the hinged closure open to permit of access to the radiator.

Fig. 3 is a vertical sectional view of the cap of this invention showing the side extensions or ornamental devices broken away and 100 partly in side elevation.

Fig. 4 is a side elevation of the locking device.

Fig. 5 is a sectional view taken on line 5—5 of Fig. 4, showing in part, a part of the cap 105 with which the locking device locks to effect a permanent attachment of the cap to the radiator.

Fig. 6 is a fragmentary side elevation of means for locking a temperature indicator or ornament or other device to the hinged closure.

5 Fig. 7 is a cross sectional view of the locking means as exemplified in Fig. 6.

In carrying out this invention the cap is made up essentially of a body portion and a hinged closure. The body portion is adapted to be screwed onto the neck of a radiator and the hinged closure provides for opening and closing the upper end of the body portion to permit of access to the neck. The body portion is composed of two main parts, 15 one of which screws onto the neck of the radiator, the other of which is locked to the first named part so that access to the first named part, to provide for unscrewing thereof after once being screwed into place, is prevented, thereby providing for permanent attachment of the cap as a whole. The locking means for locking the two parts of the body portion together is of such arrangement that during the screwing of the body 20 onto the neck of the radiator, the two parts of the body of the cap move as one and after the body is screwed onto the neck, any attempt to unscrew the same causes the locking means to immediately release and permit the 25 upper of the two parts of the body to rotate freely upon the screwed on part.

The hinged closure is associated with the body thru the instrumentality of a connecting and latching means which is of such construction and arrangement that it may be made to serve as an ornament aside from its utilitarian purposes. This is preferably accomplished by having lateral outward extensions on opposite sides of the body of the 30 cap, hinging one side of the closure cap to one of said extensions and releasably latching the opposite sides of the closure by means of the other extension, the latter extension being pivoted to the closure. Both extensions are 35 extended sufficiently beyond the sides of the body to provide wing-like ornaments, or in fact ornaments of any nature whatsoever, the said extensions, while serving as ornaments, acting at the same time as a handle portion 40 and a latch member respectively, so as to facilitate the handling of the cap in screwing the same in place and the holding thereof when opening and closing the hinged closure.

The hinged closure may be formed with 45 an opening thru the body so as to permit of the attachment of a temperature indicator, ornament or other device and thru use of a lock nut of special construction, the indicator or ornament or other device, may be 50 locked to the cap to prevent unauthorized removal or theft thereof.

Referring to the embodiment of the invention illustrated in the accompanying drawings, which embodiment exemplifies a preferred form of our invention, 1 designates a

body of the cap and 2 the hinged closure extending over the upper side of the body portion. The body portion comprises an upper part 3 of cylindrical form, and a lower part 4 of similar form, and telescoped within the 70 upper part. The lower part is formed with a reduced screw threaded portion 5 which is adapted to be screwed onto the neck 6 of an automobile radiator 7, the reduction of the lower part forms a shoulder 8 arranged to 75 engage the upper end of the neck. The upper part 3 extends over the lower part so that it will cover and protect said part against being tampered with.

We employ a novel device in connection 80 with the two parts of the body portion 1, which device will cause said parts to be locked for corresponding rotation when screwing the cap onto the neck, but will allow the upper part to revolve freely upon the lower part 85 immediately upon a turning of the cap such as would effect an unscrewing thereof, thus not affecting the lower part, which remains screwed in place. This locking device, preferably comprises a spring urged locking 90 member 9, preferably in the form of a ball which is movable in a recess 10, formed in the lower part 4 of the body. The recess 10 is preferably extended inwardly from the outside of the body so that the spring 11 will tend 95 to force the ball 9 outwardly, at all times. In the same plane as the recess 9 there is formed in the opposed wall of the upper part 3 a notch or shallow recess 12 into which the ball 9 is adapted to engage so as to lock the 100 parts 3 and 4 against relative movement. The spring urged detent or ball 9, recess 10 and notch 12 are so arranged that when the cap is turned as in screwing the lower part 105 onto the neck and the recess 10 and notch 12 register with one another, as shown in Fig. 6, the ball will extend into the recess and notch in such manner that the upper and lower parts of the body are locked against 110 relative movement and the lower part will be turned and screwed onto the neck. In turning the cap so as to unscrew the same, the ball encounters the curved or inclined face 13 of the recess 12 and, thru the cam action thus 115 provided, is forced back into the recess 10 out of the notch 12 and releases the parts 3 and 4 of the body, whereby the upper part is free to turn relative to the lower part, which latter remains screwed in place. The locking 120 device is such that once assembled, access thereto cannot be had without boring thru the parts of the body or completely destroying the construction of the cap. Preferably, we place the spring and locking member in the recess 10 and move the lower part 4 upwardly onto the upper part 3 in such manner 125 that the inner side of the upper part will engage and hold the spring urged locking member in the recess until the parts 3 and 4 are properly fitted. This locking arrangement is 130

preferably located at a point between the shoulder 8 and upper end of the lower part 4 of the body.

In order to provide for rotatably connecting the parts 3 and 4 of the body with one another so that said parts will not be capable of being disassembled after being once rotatably connected, we form in the opposed faces of the parts at a point above the locking device, complementary annular grooves 14 of a depth just sufficient to accommodate ball bearing members 15, which latter extend half into one groove and half into the other groove, as shown in Fig. 3. These balls are mounted in position by being dropped into the vertical bore 16 formed in the parts 3 and 4 of the body, said bore communicating with the complementary grooves 14. The upper end of the part 4 engages in an annular groove 18 formed in a thickened annular portion 19 of the part 3 of the body. A bore 20 is formed thru the thickened portion 19 and is adapted to register with the bore 16 to permit the balls to be dropped into place after assembling of the parts 3 and 4 of the body 1.

The upper edge of the part 3 or thickened portion 19 is formed with an annular washer groove or seat 21 in which a rubber washer or gasket 22 is snugly fitted, said washer covering the upper end of the bore 20. A plug 17 is fitted into the bore 20 so as to prevent access to the balls 15.

Extending outwardly from one side of the part 3 of the body is a handle like extension or projection 23 which, for example, may be from 3 to 4 or more inches in length so that it may be cut, stamped or cast as an ornament, for example, so as to represent a wing, as shown in the drawings. This extension is formed with an upwardly opening recess 24 which receives an ear 25 projecting outwardly from the one side of the flanged closure 2. A pivot pin 26 is mounted in the recess and ear so as to hingeably connect the closure member 2 with the body of the cap. The lower annual edge 27 of the closure 2 is adapted to engage upon the washer or gasket 22. A recess 28 is formed on the lower edge of the closure and receives the upper edge of the part 3 so as to insure proper alinement and effect a tight seal between the closure and body of the cap.

Means is provided for locking or clamping the closure in place and comprises a short projection 30, formed on the part 3 opposite to the projection 23. This projection 30 is provided with a cam face 31 on its lower side adapted to cooperate with a cam surface 32 formed in a recess 34 of a lever or locking member 35. The member 35 is preferably of the same size and shape as the projection 23 and extends from the side of the cap as does said projection 23 so as to produce symmetry of appearance in the cap as a whole and enhance the ornamental quality of the de-

vice. The lever or locking member 35 receives in the recess 34 an ear 37 which ear extends outwardly from the closure 2. A pin 38 is extended across the recess 34 and thru the ear so as to pivotally secure the lever 35 in place.

To gain access to the radiator after the cap of our invention is mounted in place, or in other words, to fill the radiator, the lever 35 is grasped and swung upwardly on its pivot 75 from its horizontal locking position, shown in Figs. 1 and 3, so that the projection 30 is withdrawn from the recess 34 and the lower side of said lever 35 clears said projection 30. The closure with the lever is then swung into 80 position shown in Fig. 2, and the radiator is ready to be filled.

To close the cap the closure is swung on its pivot into closing position and the lever 35 is moved from upright to horizontal position so that the projection 30 will extend into the recess 34. As the lever is thus moved the cam faces 31 and 32 cooperate so that a wedging action such as will tend to pull downward on the closure, takes place. As the closure is thus clamped or pulled downward, it compresses the rubber gasket 22 and in this way is yieldingly clamped to form a tight seal, when the points at X of the cam surfaces 31 and 32 engage one another. The closure is 95 thus tightly clamped in closing position and will not be subject to accidental opening incident to shocks and jars.

In screwing the cap upon a radiator, upon installing the cap, the two projections on 100 the side may serve as handle portions, whereby an effective and easy turning of the cap will be provided for. Likewise, in opening and closing the cap, the operator may grasp the handle portion or projection 23 while manipulating the similarly formed but pivoted lever locking member 35. Thus the portions 23 and 35 serve as ornaments, as convenient handles, and one of them constitutes a clamping member to hold the cap closed.

The closure 2 may be formed with an opening 39 in the top thereof where an ornament or temperature indicator, as shown in Figs. 1 and 2, may be secured to the closure by having its stem 40 extended thru the opening and affixing a special nut lock 41 to the stem within the closure. The nut lock comprises an ordinary nut 42 having a recess 43 extending therethru to the screw threads. A ball member 44 is mounted in the recess and is normally urged inwardly towards the stem by a small coil spring 45. The ball, spring and recess are so arranged that in turning the nut in place, the ball is forced into the recess and offers no resistance to such movement of the nut, but when the nut is turned as in unscrewing, the ball will be wedged between the nut and stem so as to prevent unscrewing of the nut. After the ball and spring are inserted the recess 43 is plugged as at 44 to prevent tampering with 130

the locking means. After the nut is put on the stem, the device A is permanently held upon the closure 2 and is safeguarded against theft, independent of the cap, and the entire 5 cap and device A is, as a whole, securely and permanently held and locked against removal from the radiator.

We claim:

1. A closure cap embodying in its construction 10 a body portion having an opening therein and arranged so that it may be screwed onto the neck of the radiator of an automobile or like vehicle, means which after the body portion is screwed in place will prevent unscrewing of said body portion, a closure hinged to the body portion and arranged to be moved into and out of position for closing 15 said opening, like extensions projecting from opposite sides of the body portion and to both of which extensions said closure is pivotally connected, one of said extensions being rigid with the body portion and the other of said extensions being capable of movement relative to said body portion and means cooperating 20 with the last named extension to provide for clamping and unclamping of said closure.

2. A radiator cap comprising a body portion 25 adapted to be fitted upon the neck of a radiator, projections extending outwardly from opposite sides of said body, a closure pivoted on opposite sides to the said projections, one of said projections being rigidly supported by the body and means associated 30 with the body and with which the other projection cooperates to clamp the closure upon the body.

3. A radiator cap comprising a body portion 35 adapted to be fitted upon the neck of a radiator, like projections extending outwardly from opposite sides of said body, a closure pivoted on opposite sides to the said projections, one of said projections being rigidly supported by the body, and means associated 40 with the body and with which the other projection cooperates to clamp the closure upon the body.

4. In combination with a radiator cap, of a device supported on the cap, a screw threaded stem on said device extending thru said cap,

a nut turned on the stem beneath said cap 50 and means in the nut which when the nut is turned as in unscrewing the same, will wedge between the nut and stem and prevent unscrewing of the nut.

5. The combination of an internal collar 55 having an opening therethrough and having external threads for attachment to the internally threaded filling opening of a radiator, an external collar fitting around said internal collar and adapted to terminate adjacent the 60 end of the said internally threaded opening, a closure for said external collar having an opening adapted to receive a motometer, a pivot pin permanently securing said closure to the external collar, and means locking together 65 said collars against theft.

6. The combination of an internal collar having an opening therethrough and having external threads for attachment to the internally threaded filling opening of a radiator, 70 an external collar surrounding said internal collar and adapted to terminate adjacent the end of the said internally threaded opening, a closure for said external collar adapted to carry an auxiliary device, a pivot pin permanently securing said closure to the external collar, and means maintaining said collars in assembled relation against theft.

7. Means for locking a radiator cap to a radiator comprising an internal collar adapted to fit a radiator nipple, locking means preventing the removal of the cap from said collar but permitting relative rotation between said parts, and protective means preventing access to said collar from the interior 85 of said cap.

8. Means for locking a radiator cap to a radiator comprising an internal collar adapted to fit a radiator nipple, locking means permitting rotation of said cap about said collar 90 in one direction only, and a second collar adapted to fit over said internal collar, a downwardly extending skirt on said second collar, said skirt functioning to protect said internal collar against access interiorly of 95 said cap.
